UNITED STATES PATENT OFFICE.

EDMUND PHILO KELLOGG, OF CHICAGO, ILLINOIS, ASSIGNOR TO ALBERT PICK & COMPANY, OF CHICAGO, ILLINOIS, A CORPORATION OF ILLINOIS.

DESIGN FOR A CANDY BOX.

Application filed February 11, 1921. Serial No. 444,295. Term of patent 3½ years.

To all whom it may concern:

Be it known that I, EDMUND PHILO KELLOGG, a citizen of the United States, residing at Chicago, in the county of Cook and State of Illinois, have invented a new, original, and ornamental Design for a Candy Box, of which the following is a specification, reference being had to the accompanying drawing, forming a part thereof.

The drawing is a perspective of a candy box embodying the invention.

I claim:

The ornamental design for a candy box as shown.

EDMUND PHILO KELLOGG.
